UNITED STATES PATENT OFFICE

137,753

DESIGN FOR A SPECTACLE FRAME

Eudice Rey, Brooklyn, N. Y., assignor to Zyloware Corporation, Long Island City, N. Y.

Application February 1, 1944, Serial No. 112,403

Term of patent 14 years

(Cl. D57—1)

To all whom it may concern:

Be it known that I, Eudice Rey, a citizen of the United States of America, residing at Brooklyn, in the county of Kings, New York, New York, have invented a new, original, and ornamental Design for a Spectacle Frame, of which the following is a specification, reference being had to the accompanying drawing, forming part thereof.

I claim:

The ornamental design for a spectacle frame, as shown and described.

EUDICE REY.
